VAPORIZER

Gustav Axel Peterson, Stamford, Conn., assignor
to Electrolux Corporation, New York, N. Y., a
corporation of Delaware

Application September 13, 1939, Serial No. 294,673

5 Claims. (Cl. 21—127)

My invention relates to a vaporizer for vaporizing a solid which is capable of sublimation. More especially, my invention relates to a vaporizer of this type which is adapted to be used in conjunction with a vacuum cleaner and which may be connected directly to an air flow opening in the cleaner. The vapor produced may be discharged directly from the vaporizer into the surrounding atmosphere, or a hose or other conduit may be connected to the outlet of the vaporizer for conducting the vapor to any desired locality.

My invention also includes an improved form of coupling device for releasably securing two fluid conveying elements together, and more specifically for connecting the vaporizer to the vacuum cleaner.

Further objects and advantages of my invention will be apparent from the following description considered in connection with the accompanying drawing, which forms a part of this specification and of which—

Fig. 1 is a side view of a vaporizer in accordance with my invention connected to the outlet of a vacuum cleaner, and having a hose connected to the outlet of the vaporizer;

Fig. 2 is a view, chiefly in cross-section, of the vaporizer shown in Fig. 1, together with the portion of the vacuum cleaner to which the vaporizer is connected;

Fig. 3 is an elevational view of a member forming part of the vaporizer; and

Fig. 4 is an elevational view, partially broken away, showing a vaporizer in accordance with the invention with the crystals in the position which they occupy immediately after having been placed therein.

Referring to the drawing, reference character 10 designates generally the improved vaporizer in accordance with my invention, while reference character 11 designates a vacuum cleaner unit to which the vaporizer is removably connected, and reference character 12 designates generally a hose or other conduit which may be connected to the vaporizer. As shown, the vacuum cleaner 11 is provided with runners 13 or other suitable means for supporting it in a substantially horizontal position. One end of the vacuum cleaner is provided with an air inlet opening 14, while the other end is provided with an exhaust opening 15. Exhaust opening 15 is formed in an end-cap 16, as is best seen from Fig. 2.

As shown, vaporizer 10 constitutes a hollow body which may be made in two parts 17 and 18, which are permanently joined together in sub-

stantially air-tight relationship along the seam 19. The part 17 is formed with an end portion 20 of reduced diameter. The external diameter of portion 20 is such that it fits closely within a sleeve 21 secured within the exhaust opening 15. This sleeve is formed with an inturned lip 22, the inner face of which is adapted to be engaged by projections 23 which are carried by latch members 24 and which project through apertures formed in the wall of end portion 20. One end of each latch member extends through an additional aperture in portion 20, so as to be accessible from outside the vaporizer, as is shown at 25. The opposite end of each latch member is pivotally mounted within a space 26 formed by turning in the end of portion 20. A circular spring 27 is arranged to engage the latch members 24 so as to tend to force them radially outwardly, thus causing both the projections 23 and 20 the ends 25 to project as far as possible through their respective apertures. Each projection is formed with an inclined surface facing the end of portion 20 and a substantially radial surface facing in the opposite direction.

Reference character 28 designates a cup-shaped member, the outer diameter of the greater portion of which is such as to fit snugly within the inturned end of portion 20. In addition, member 28 is formed at one end with a reverse flange 29, the inner diameter of which is such as to fit snugly over portion 20. Portion 20 is formed with a shoulder 30 against which the edge of flange 29 may seat, thus limiting inward movement of the member 28. The opposite end 30 of member 28 is slit along lines which lie in radial planes, as is indicated at 31. The material adjacent to one side of each slit is displaced inwardly so as to form opening 32 having substantial cross-sectional area. The walls of member 28 intermediate its ends may be formed with slight outwardly extending ridges 33, the purpose of which is to prevent accidental displacement of the member should the frictional engagement between the member and the turned-in end of portion 20 not be sufficient for this purpose. These projections are able to pass the turned-in end of portion 20 by slightly deflecting the material.

Part 18 of the vaporizer is likewise formed with an end portion 34 of somewhat reduced diameter but larger than end portion 20. The end of portion 34 is formed with a reverse internal flange 35 forming a shoulder 36. Portion 34 is adapted to receive a coupling member 37 secured to the end of hose 12, which coupling member

may be in all respects similar to the coupling carried by portion 26. The projections 23 of this coupling member engage the flange 36 to hold the coupling in place. Two vaporizers may be connected in series, as desired, by inserting the end portion 20 of one in the end portion 34 of the other.

Located within part 18 adjacent to the outlet opening formed by portion 34 is a perforated wall 38. This wall may consist of a fine screen or, as is shown, of a sheet of metal provided with perforations 39.

Extending inwardly from the rear wall 40 of member 16 of the vacuum cleaner is a plurality of rod-like members 41, the inner ends of which support a plate 42. Slidably supported on rods 41 is a member 43 in the form of a rim bounding a central opening. A plurality of inclined vanes 44 extend across this opening. A coil spring 45 is disposed between plate 42 and member 43 and tends to urge the member to the right, as viewed in Fig. 2. When the vaporizer is not connected to the vacuum cleaner, this spring holds the member 43 against the shoulder 22 of sleeve 21.

The operation of the above-described device 25 is as follows:

When the vacuum cleaner is used for ordinary cleaning purposes, the hose 12 is connected to the inlet opening 14. The vacuum cleaner includes a motor-fan unit arranged to draw air inwardly through the inlet and through the hose connected thereto. In the event that neither the hose nor the vaporizer is connected to the outlet 15, the spring 45 holds the member 43 against the shoulder 22 as just described. Hence, the inclined vanes 44 are disposed immediately in the outlet opening and cause the air discharged therethrough from the motor-fan unit to be directed upwardly and away from the surface which supports the cleaner.

In the event that it is desired to employ the vaporizer, the member 28 is removed therefrom, thus providing an unobstructed entrance of substantial area into the vaporizer. The vaporizer is then preferably held in a vertical position, as shown in Fig. 4 and suitable crystals, such as paradichlorobenzene are introduced through the unobstructed opening. The member 28 is then inserted into the portion 20 and the vaporizer is connected to the outlet of the vacuum cleaner by merely placing the end thereof against the member 43 and pushing inwardly. This causes the member 43 to slide on the rods 41 while compressing the spring 45. When the projections 23 on the latch members 24 strike the outer edge of the shoulder 22, the inclined surface of the projections cause them to be displaced inwardly against the force of spring 27. However, as soon as the projections have passed the shoulder, spring 27 forces them outwardly and the radial surfaces thereon engage the inner edge of shoulder 22. Spring 45 urges member 44 against the end of the vaporizer, thus holding the projections tightly against this shoulder so as to provide a firm connection.

If it is desired to treat the entire space within which the cleaner may be located, for instance a closet, it is not necessary to connect the hose 12 to the outlet of the vaporizer, but the vapor may be discharged directly into such space. To do this the motor fan unit is started which causes air to be discharged between the vanes 44 into the interior of member 28. This air passes through the openings 32 and, because of the loca-

tion and arrangement of these openings, it flows thereto in a tangential direction. This in turn results in a whirling of the air within the vaporizer which picks up the crystals and keeps them in a constant state of agitation, thus increasing the rate of vaporization. The crystals are whirled in a plane parallel to the plane of the perforated wall 38, whereby there is little tendency for them to be piled up against this wall by the air flowing through the perforations. The air and vapor formed within the vaporizer are discharged together through the portion 34.

If it is desired to convey the vapor to a space in which it is not convenient to place the vacuum cleaner, the hose 12 may be connected to the portion 34 of the vaporizer, and the other end of the hose introduced into such space.

When it is desired to remove the vaporizer from the vacuum cleaner, it is merely necessary to press inwardly on the ends 25 of the latch members 24. This in turn causes the projections 23 to be retracted from engagement with the shoulder 22, whereupon the spring 45 acts to eject the vaporizer from the outlet of the vacuum cleaner.

While I have shown one more or less specific embodiment of my invention, it is to be understood that this has been done for purposes of illustration only, and is not to be considered as a limitation of my invention, the scope of which is to be determined by the appended claims.

What I claim is:

1. A vaporizer attachment for a pneumatically operated device comprising a hollow body of sufficient size to receive particles to be vaporized, said body having two openings therein, means to substantially prevent the escape of said particles through one of said openings while permitting the flow of air therethrough, a tube open at both ends extending outwardly from the other of said openings, a second tube open at both ends mounted within the first tube with its axis roughly parallel to that of the first tube, said second tube being sufficiently smaller in cross section than the first tube to provide a substantial space therebetween, means closing the end of said space at the end thereof furthest from said body, said second tube having impervious walls and extending at least substantially to said other of said openings in said hollow body, means for substantially preventing the escape of said particles through said second tube and for guiding air flowing out of the second tube into the hollow body to cause it to leave the second tube in a generally radial direction, latch means disposed within said space for quick-detachably engaging an exhaust opening in said device, and manually operable means extending from said space through an aperture in the first tube for releasing said latch means.

2. A vaporizer attachment for a pneumatically operated device comprising a hollow body of sufficient size to receive particles to be vaporized, said body having two openings therein, means to substantially prevent the escape of said particles through one of said openings while permitting the flow of air therethrough, a tube open at both ends extending outwardly from the other of said openings, a second tube open at one end mounted concentrically within the first tube, the diameter of the second tube being sufficiently smaller than that of the first tube to provide an annular space therebetween, an outturned reverse flange on the open end of the second tube removably engaging the free end of the first tube.

said free end being of sufficiently reduced diameter that the outer diameter of said reverse flange is no greater than the outer diameter of the first tube, said second tube having impervious walls and extending at least substantially to said other of said openings in said hollow body, the other end of said second tube being partially closed by a wall having apertures therein permitting air to flow therethrough, said wall substantially preventing the escape of said particles from said body, the portions of said wall adjacent said apertures being formed to direct air passing therethrough radially outward into said body, latch means disposed within said space for quick-detachably engaging an exhaust opening in said device, and manually operable means extending from said space through an aperture in the first tube for releasing said latch means.

3. A vaporizer attachment for a pneumatically operated device comprising a hollow body of sufficient size to receive particles to be vaporized, said body having two openings therein, means to substantially prevent the escape of said particles through one of said openings while permitting the flow of air therethrough, a tube open at both ends extending outwardly from the other of said openings, a second tube open at one end mounted concentrically within the first tube, the diameter of the second tube being sufficiently smaller than that of the first tube to provide an annular space therebetween, an outturned reverse flange on the open end of the second tube removably engaging the free end of the first tube, said free end being of sufficiently reduced diameter that the outer diameter of said reverse flange is no greater than the outer diameter of the first tube, an inturned reverse flange on the free end of the first tube, the inner diameter of said inturned reverse flange being just large enough to receive and frictionally engage the outer diameter of said second tube, said second tube having impervious walls and extending at least substantially to said other of said openings in said hollow body, the other end of said second tube being partially closed by a wall having apertures therein permitting air to flow therethrough, said wall substantially preventing the escape of said particles from said body, the portions of said wall adjacent said apertures being formed to direct air passing therethrough radially outward into said body, latch means disposed within said space for quick-detachably engaging an exhaust opening in said device, and manually operable means extending from said space through an aperture in the first tube for releasing said latch means.

4. A vaporizer attachment for a pneumatically operated device comprising a hollow body of sufficient size to receive particles to be vaporized, said body having two openings therein, means to substantially prevent the escape of said particles through one of said openings while permitting the flow of air therethrough, a tube open at both ends extending outwardly from the other of said openings, a second tube open at one end mounted concentrically within the first tube, the diameter of the second tube being sufficiently smaller than that of the first tube to provide an annular space therebetween, an outturned reverse flange on the open end of the second tube removably engaging the free end of the first tube, said free end be-

ing of sufficiently reduced diameter that the outer diameter of said reverse flange is no greater than the outer diameter of the first tube, an inturned reverse flange on the free end of the first tube, the inner diameter of said inturned reverse flange being just large enough to receive and frictionally engage the outer diameter of said second tube, slight protrusions on the otherwise cylindrical outer surface of said second tube, said protrusions lying just adjacent to the end of the inturned reverse flange on the side thereof adjacent the hollow body when said second tube is in place thereby resisting removal of said second tube, said second tube having impervious walls and extending at least substantially to said other of said openings in said hollow body, the other end of said second tube being partially closed by a wall having apertures therein permitting air to flow therethrough, said wall substantially preventing the escape of said particles from said body, the portions of said wall adjacent said apertures being formed to direct air passing therethrough radially outward into said body, latch means disposed within said space for quick-detachably engaging an exhaust opening in said device, and manually operable means extending from said space through an aperture in the first tube for releasing said latch means.

5. A vaporizer attachment for a pneumatically operated device comprising a hollow body of sufficient size to receive particles to be vaporized, said body having two openings therein, means to substantially prevent the escape of said particles through one of said openings while permitting the flow of air therethrough, a tube open at both ends extending outwardly from the other of said openings, a second tube open at one end mounted concentrically within the first tube, the diameter of the second tube being sufficiently smaller than that of the first tube to provide an annular space therebetween, an outturned reverse flange on the open end of the second tube removably engaging the free end of the first tube, said free end being of sufficiently reduced diameter that the outer diameter of said reverse flange is no greater than the outer diameter of the first tube, an inturned reverse flange on the free end of the first tube, the inner diameter of said inturned reverse flange being just large enough to receive and frictionally engage the outer diameter of said second tube, said second tube having impervious walls and extending at least substantially to said other of said openings in said hollow body, the other end of said second tube being partially closed by a wall having apertures therein permitting air to flow therethrough, said wall substantially preventing the escape of said particles from said body, the portions of said wall adjacent said apertures being formed to direct air passing therethrough radially outward into said body, latch means disposed within said space for quick-detachably engaging an exhaust opening in said device, said latch means comprising a member pivoted to the first tube within the annular space formed by the inturned reverse flange, and manually operable means extending from said space through an aperture in the first tube for releasing said latch means.
